T. ELLIOTT

RAILWAY CAR

Filed Aug. 11, 1922

Inventez

Thomas Elliott,

By Pauline Pauline,

Affirmans

UNITED STATES PATENT OFFICE.

THOMAS ELLIOTT, OF CINCINNATI, OHIO, ASSIGNOR TO THE CINCINNATI CAR COMPANY, OF CINCINNATI, OHIO, A CORPORATION OF OHIO.

RAILWAY CAR.

Application filed August 11, 1922. Serial No. 581,069.

To all whom it may concern:

Be it known that I, THOMAS ELLIOTT, a citizen of the United States, residing at Cincinnati, in the county of Hamilton and 5 State of Ohio, have invented certain new and useful Improvements in Railway Cars, of which the following is a specification, reference being had therein to the accompanying drawing.

10 This invention relates to improvements in railway cars, particularly the kind used on street railway lines and on interurban roads.

One object of the invention is to provide 15 an anchor device which shall secure the posts to the belt rail and, preferably, incidentally also secure the window sill between the belt rail and the post.

And a further object of my invention is 20 to facilitate the ready assembling of the sashes with the posts and the easy removal of the sashes, as occasion requires, which I accomplish by metallic pilasters adapted to be connected with the posts and maintain the sashes in place.

25 In the accompanying drawings:—

Fig. 1 is a vertical sectional view, on an enlarged scale, of one side of a car body embodying my invention;

Fig. 2 is another enlarged vertical sectional view showing the relation of the belt rail, rib, side post and anchor;

Fig. 3 is a cross section of the side post on the line 3—3 of Fig. 1;

Fig. 4 is a transverse sectional view on 25 the line 4—4 of Fig. 1, showing more particularly the metal pilaster to retain the upper sash; and

Fig. 5 is a vertical sectional view, enlarged and in detail, of a metallic post 40 chair.

Referring to Fig. 1 it will be seen that instead of the common construction of a side post extending from the body floor in a continuous piece to the roof, and in some instances, in a continuous piece from the floor at one side of the car to the floor at the other, thus including in one piece two posts and a rafter, I have departed from that type of construction and fashioned 45 these major framing members of ribs 1 which extend from the floor or sill 6 to the point where the belt rail 2 is located. On the belt rail I mount the window sill 3,

over which I fit a post-chair 3^a constructed of metal, preferably cast. This chair has 55 a base portion 3^b with end shoulders 3^c and 3^d formed, respectively, on the flanges 3^e and 3^f. The flanges 3^e and 3^f, in the lower portion, form a sort of leg for the chair to support the base portion 3^b in practically 60 horizontal position, while the flange 3^f overlaps the inner part of the belt rail 2. The half post is seated on the base 3^b and between shoulders 3^c and 3^d. The chair is further provided with a bolt opening 3^g 65 for the passage of the anchor bolt to be presently referred to. On this chair I place the side post 4, as more clearly seen in Fig. 2. The side post extends from the rail to near the roof, where it is secured in any 70 desired manner, preferably that indicated in the upper part of Fig. 1, a construction which is set forth in my pending case, Ser. No. 553,653, filed April 17, 1922. The side post is grooved at 5, as shown best in Fig. 75 3, to receive the lower sash 7. Fig. 3 shows a cross section of the post 4, and its groove 5 for the lower sash, as also the groove 5^a for the curtain, with the curtain-retaining strips of metal 5^b.

The post 4 is anchored at its lower end to that part of the structure which is below the post, by means of the anchor bolt 8 and the belt rail 2 which is joined, as by rivets 2^a, to the body plate 2^b, and which, in turn, 85 is secured in any of the usual ways to the ribs 1. The post 4 is bored out at an inclination, as shown in Fig. 2, to receive the anchor bolt whose upper end is screwed or otherwise united with an anchor block 8^a. 90 The bolt extends through the chair 3^a, the sill 3, the belt rail 2 and the flange portion 2^c of the rib. At this lower end the anchor bolt is threaded and a nut 9 is applied, by which all these parts are drawn and tightly 95 bound together, and the foot of the side post duly anchored to the lower portion of the structure.

It will be seen that besides anchoring the post to the lower structure of the body the 100 action of the anchor is also that of clamping the window sill to the belt rail and securing the post so that rain and other moisture will be excluded.

The lower sash 7 is fitted to slide in the 105 way 5 behind the metal pilaster 6^a. This

pilaster extends from the belt rail 2 upward along and over the half post until it reaches the lower cross bar of the upper sash 10. It is secured in any desired manner to the 5 post, preferably by screws 6^b. The sash 7 is readily and quickly assembled in position before the pilaster 6^a is applied and then the positioning of the pilaster on the post maintains the sash in place.

- 10 The numeral 11 designates the upper metal pilaster for retaining the upper sash 10 in its place in the recess 12 formed in the upper face of the post 4. This pilaster is secured in any desired manner. At its 15 lower end it fits under the lower bar of the upper sash 10 and at its upper end under the lower edge of the letter board 13.

It will be seen that by the construction described I provide a strong and durable 20 manner of mounting and securing the lower end of the half posts, as also securing the window sills to the belt rail. And further, that I also afford a convenient and ready 25 means of assembling the sashes with the posts and of maintaining them in their appropriate places by means of the lower metallic pilasters 6 and the upper metallic pilasters 11.

Having thus fully described my invention, 30 what I claim as new and desire to secure by Letters Patent, is:—

1. In a car body, the combination with 35 ribs built into the lower structure, and a belt rail secured above the ribs, of posts located in the structure above the belt rail and anchors to secure the posts to the belt rail.

2. In a car body, the combination with 40 ribs built into the lower structure and a belt rail extending over and inward of the ribs and secured, of side posts built into the upper structure and extending from near the belt rail to near the roof, and anchors adapted to secure the posts to the belt rail.

45 3. In a car body, the combination with ribs and a belt rail above them, of a window sill on the belt rail and side posts above the sill, and an anchor acting to bind and secure together the belt rail, the sill and the posts and thereby the posts to the ribs.

50 4. In a car body, the combination with ribs and a belt rail, of side posts and anchor bolts imbedded in the posts and extending through the belt rail and having nuts to 55 clamp the parts together.

5. In a car body, the combination with 60 ribs, a belt rail and a window sill on the rail, of side posts on the sill and bolts anchored in the posts and extending through the sill and the belt rail and provided with binding nuts.

6. In a car body, the combination with 65 ribs in the lower structure, body plates secured to the ribs, a belt rail secured to such plates and extending over and inward of the

70 ribs, of a sill on the belt rail, side posts above the sill, window sashes slidably mounted in the posts, and a bolt anchored in each post and extended through the sill and the belt rail provided with a binding nut.

7. In a car body, the combination with 75 a lower structure comprising a sill, ribs and body plates, and a belt rail secured to such plates, of an upper structure including window sills mounted on the belt rail, posts above the window sill, sashes carried by the posts, and an anchor acting to bind the posts and sill to the belt rail.

8. In a car body, the combination with 80 ribs built into the lower structure, and a belt rail secured above the ribs, of posts located in the structure above the belt rail, a chair at the foot of each post, a sill between the chair and the belt rail, and anchors to secure the posts to the belt rail and down in the chairs.

85 9. In a car body, the combination with a belt rail secured to the car body and a side post, of a chair adapted to rest on the belt 90 rail and receive the lower end of the post and means to secure the post in the chair.

10. In a car body, the combination with 95 a belt rail secured to the car body, a side post, and a chair adapted to rest on the belt 100 rail and receive the lower end of the post, of an anchor bolt secured to the post and adapted to extend through the chair and belt rail and provided with a nut, whereby the post and chair are firmly held together.

11. In a car body, the combination of a 105 side post, a pilaster on the outer face of the post having inward projections fitting around the adjacent side face of the post, and abutments integral with the post co-operating with the projections of the pilaster to form sash guideways.

12. In a car body, the combination with a 110 side post having its outer edges reduced and a removable metallic pilaster on its outer face and having inward projections fitting over the outer marginal edges of the post and to leave a way or space between it and a portion of the post, to form a guide 115 for a movable sash.

13. In a car body the combination with a side post having its outer edges rabbetted, and a removable pilaster positioned on the outer face of the post and extending for a distance upwardly of the post, said pilaster having inwardly extending portions fitting over a marginal portion of adjacent side faces of the post and cooperating with the rabbetted portion to form sash guideways, the outer face of said posts not covered by said pilaster being recessed, a stationary sash fitted into said recess, and a second removable pilaster overlying the sash and securing said stationary sash to the latter.

14 In a car body the combination with of the incline, whereby the seat is main-
an inclined belt rail, of a post chair com- tained substantially horizontal, a post rest-
prising a body having a seat for the end ing on said seat, and means for securing 10
of a post and having outer and inner side said post, chair and rail together.
5 flanges, the inner side flange fitting over the In testimony whereof, I affix my signa-
upper end of the inclined belt rail and the ture.
outer flange resting on the lower portion

THOMAS ELLIOTT.
